UNITED STATES PATENT OFFICE.

CLAIR D. STONE, OF CHICAGO, ILLINOIS.

DESIGN FOR A BUTTON.

SPECIFICATION forming part of Design No. 19,481, dated December 10, 1889.

Application filed October 28, 1889. Serial No. 328,479. Term of patent 3½ years.

To all whom it may concern:

Be it known that I, CLAIR D. STONE, a citizen of the United States, residing at Chicago, in the county of Cook and State of Illinois, have invented and produced a new and original Design for Buttons, of which the following is a specification, reference being had to the accompanying drawings forming part thereof.

10 Figure 1 is a face view of a button showing my design and Fig. 2 is a sectional perspective view, these two views being deemed necessary to fully illustrate my design.

The leading feature of my design consists 15 in a raised face with lines and an irregular figure worked thereon, which, when viewed in elevation, will produce a globular appearance, representing the earth in miniature. The contour of the face A is slightly curved 20 in the center and more sharply curved at the edges. The background or plain part a of the surface has lines a' running through the poles, and transverse lines a² run so as to represent parallel lines on a globular surface.

The irregular figure b is produced by roughening that part of the surface which it occupies, so as to make it appear clearly distinguishable from the background or part a. The lettering C is largest in the center and gradually diminishing toward the edges to 30 carry out the globular effect.

What I claim is—

The design for a button herein shown and described, the same consisting in a circular raised face representing in section an arc or 35 slightly-flattened elliptic curve, said face being ornamented in background with longitudinal-curved lines converging toward poles at opposite edges of the face, transverse lines curved and diverging as they approach opposite edges of the face, and an irregular figure b, worked on said background, the whole giving the effect of a globe, as set forth.

CLAIR D. STONE.
